UNITED STATES PATENT OFFICE

102,963

DESIGN FOR A DUPLICATING MACHINE SIDE CASING OR SIMILAR ARTICLE

Paul T. Trueman, Canton, Mass., assignor to
Standard Mailing Machines Company, Everett,
Mass., a corporation of Massachusetts

Application October 20, 1936, Serial No. 65,389

Term of patent 14 years

To all whom it may concern:

Be it known that I, Paul T. Trueman, a citizen of the United States, residing at Canton, in the county of Norfolk, and Commonwealth of Massachusetts, have invented a new, original, and ornamental Design for a Duplicating Machine Side Casing or Similar Article, of which the following is a specification, reference being had to the accompanying drawing forming part thereof.

Fig. 1 is a side elevation of one of my duplicating machine side casings or similar article.

Fig. 2 is a side elevation of an opposed side frame.

Fig. 3 is a plan view of the part as shown at Fig. 1.

Fig. 4 is an end view of my side casing.

Fig. 5 is a vertical section taken substantially along line 5—5, Fig. 1.

What I claim is:

The ornamental design for a duplicating machine side casing or similar article as shown.

PAUL T. TRUEMAN.
